CLARK D. PAGE, OF ROCHESTER, NEW YORK.

Letters Patent No. 82,023, dated September 8, 1868.

IMPROVED LIME-KILN.

The Schedule referred to in these Letters Patent and making part of the same.

TO ALL WHOM IT MAY CONCERN:

Be it known that I, CLARK D. PAGE, of Rochester, in the county of Monroe, and State of New York, have invented a certain new and useful Improvement in Lime-Kilns; and I do hereby declare that the following is a full and exact description thereof, reference being had to the accompanying drawings, making part of this specification.

Figure 1 is an elevation.

Figure 2, a plan.

Figure 3, a central vertical section.

Figure 4, a cross-section in plane of line x x , fig. 3.

Like letters of reference indicate corresponding parts in all the figures.

This invention relates to the employment of stay-pieces to brace the kiln, with air-flues to keep them from burning; to the employment of shielded poke-holes at the top of the kiln for shaking down the stove, and the construction and arrangement of the furnace and grate-bars, all as hereinafter described.

In the drawings, A indicates the kiln, constructed of stone, as usual. In the sides are built strips a a a , of plank, overlapping each other at the corners, as shown, and suitably secured together. Inside each strip is made an air-flue, b, extending longitudinally the whole length, and opening out so as to allow a free passage of air from end to end.

These strips serve as binders to the stack, to prevent rupture and displacement. Being made of wood, they yield, to adapt themselves to the expansion and contraction of the stack under different temperatures, which would not be the case were they made of iron or other inflexible material. The flues serve simply to secure a passage of cold air inside the binders, which keeps them cool, and thus effectually prevents either burning out or deadening of the wood. This combination of wooden binders with inside air-flues is necessary to secure elasticity and durability.

The hopper B is subjected to considerable strain, and is surrounded by heavy timber binders a' a' a' a' , similar to a a , except that as but little heat comes so high, the air-flues are not employed.

The hopper is made of the usual flaring form. Opposite the corners are made poke-holes c c c c , just back of the hopper, the wall d of which inclines or shields the holes so as to isolate or shut them off from the hopper. These holes open inward at the proper distance down, as indicated most clearly in fig. 3.

The great advantage of these poke-holes is, that they open downward, in the direction of the cupola, so that the thrust will be longitudinal, thus always loosening and dislodging the rock; and, at the same time being shielded or cut off from the body of the hopper, there is no impediment to the free action of the poker, as there would be if the holes were dispensed with and the poker simply run down in the hopper itself. In such case the impediment would be so great that the poker could not easily reach that point where there is the greatest difficulty from clogging, and just the place where my poke-holes open into the hopper. These poke-holes also allow a free shaking motion of the poker to loosen the rock.

The ordinary lateral poke-holes c' c' are also employed.

I construct my furnace-arches with flaring sides f f , and with loose grate-bars g g , which may be removed separately from place. At the sides of the grate-bars are made vertical side-passages h h , for the free entrance of air at the sides of the furnace, as well as up through the grates. These side-passages are of much importance, for the tendency of the fire is to concentrate in the centre of the furnace, where the greatest amount of fuel is, and where the greatest amount of the air comes. These passages admit a heavy body of air at the sides, and thus serve to equalize the burning, and produce a more perfect combustion. These passages also catch the air, and, in carrying it up in a series of equalized currents the whole extent of the furnace, retain it from concentrating at once in a body at the inner or further end of the furnace, as where the walls are smooth and unbroken. These passages, by breaking the smoothness of the wall, and by furnishing air inside the general surface, effectually prevent clinkering.

The grate-bars stand in an inclined position, as shown in fig. 3. Their inner ends rest in a fixed, notched

bar, *i*, and do not quite touch the inner wall of the furnace, so that they are enabled to shake freely there, and avoid burning out by not resting on a shoulder. Their outer central portions rest on a fixed bar, *k*, that extends through from side to side of the stack, and thus serves as a binder; and the extreme outer ends rest on a notched bar, *l*, pivoted at *l*, so as to turn up or down, and held up by a pin, *m*, or equivalent, when in use. This bar is simply for retaining the grates from lateral displacement.

When the bars are to be shaken, the hinged bar *i* is lowered, as in red lines, fig. 1, which leaves the grates resting intermediately on bar *k*, which serves as a fulcrum; and the leverage but slightly preponderating in one direction, they are easily shaken. The bar *k* being smooth, and the inner ends of the grates being free, as before described, allows a free lateral action, which is most effective in removing clinkers. The leverage also allows the grates to be raised vertically, as in red lines, fig. 3. These advantages are too apparent to require further description.

In the bottom of the ash-pits are situated pans *p p*, for holding water. These pits have an outward incline from the grate downward, as shown at *q*, and their bottom is sunk at some distance below the level of the outer entrance or door, as shown at *r*. This construction holds the water and ashes at such a depth as not to be affected by the incoming draught, and at the same time the incline *q* carries the air up in an unbroken body to the inner end of the furnace, bathing the whole inner ends of the grates, so that they cannot easily burn out.

The top of the cupola proper is made somewhat flaring upward, as shown at *s*; and above this the hopper *B* is made with a still greater outward angle, as shown at *t*. These two angles form an enlarged mouth at the top of the cupola, in which the raw stone is placed preparatory to going down into the kiln. This stone becomes gradually heated, and attains its maximum of expansion before it enters the narrow passage. This expansion, from the flaring shape of the mouth, acts outwardly and upwardly, without in any degree straining upon the walls. I thus obviate a great difficulty experienced in ordinary kilns, from the swelling of the stone inside. This enlarged form of the mouth also facilitates the entrance of the stone.

What I claim as my invention, and desire to secure by Letters Patent, is—

1. The combination and arrangement, with the grate-bars *g g*, of the cross-bars *k i*, the first being fixed, and forming a fulcrum for the leverage of the grate-bars in shaking, and the latter being hinged, so as to turn up and down to secure the grates, or allow them to be shaken, as herein set forth.
2. The flues *b*, constructed as described, next to the inner edge of the wooden binders *a* of the kiln, to operate in the manner and for the purpose substantially as described.

In witness whereof, I have hereunto signed my name in the presence of two subscribing witnesses.

C. D. PAGE.
